UNITED STATES PATENT OFFICE.

HARRIET RUTH TRACY, OF LONDON, ENGLAND.

SHUTTLE FOR SEWING-MACHINES.

SPECIFICATION forming part of Letters Patent No. 704,406, dated July 8, 1902.

Application filed March 21, 1899. Serial No. 709,925. (No model.)

To all whom it may concern:

Be it known that I, HARRIET RUTH TRACY, a citizen of the United States of America, residing at London, England, have invented 5 certain new and useful Improvements in or Relating to the Shuttles of Sewing-Machines, (for which I have made application for Letters Patent in Great Britain under No. 1,135, dated January 17, 1899,) of which the following is a specification.

This invention relates to that class of sewing-machines in which a vibratory or reciprocating shuttle is employed. In all such machines as heretofore constructed it has been 15 necessary to have an independent device which takes up the slack or loop made by the shuttle in the formation of each stitch. The object of this invention is to so construct a vibratory shuttle that this slack or loop 20 (which is commonly referred to in the art as the "shuttle-slack") is held back and used for the succeeding stitch, any independent take-up being thus dispensed with. By this invention, therefore, (instead of the portion of 25 the needle-thread which forms the loop being drawn back and forth many times through the work and the eye of the needle as loops are formed and taken up,) the loop when once formed is retained below the work and used 30 for a succession of stitches, the shuttle after the formation of the first loop at each successive stitch adding merely such a quantity of thread to the loop as has been used up in the work to form a stitch. The shuttle can 35 therefore be made larger than has been hitherto practicable, so as to carry any desired bulk of thread or other sewing material.

In carrying out the invention I affix at or near the back end of the shuttle, which may 40 be of any usual shape, an arm, bar, rod, or the like extending forward and preferably above and to one side to within a short distance of the front end of the shuttle. The loop of the needle-thread after passing over 45 the body of the shuttle is engaged between the arm and the shuttle, so that the slack is taken up by each complete reciprocation of the shuttle.

A convenient form of construction for carrying out this invention is shown in the accompanying drawings, in which—

Figures 1 and 2 are plan views of a shuttle,

having an arm, according to this invention, in different operative positions. Fig. 3 is a section of the shuttle on the line 3 3 of Fig. 55 1. Figs. 4 and 5 are diagrammatic side views of a shuttle in the operative positions shown in Figs. 1 and 2, respectively, showing the relative positions of the needle and its thread.

Like letters indicate like parts in all the 60 figures.

The shuttle A, which may be of any usual shape and reciprocates, as shown, in the arc of a circle or in a straight line, as preferred, is provided with an arm B, fastened in any 65 convenient manner to the back of the shuttle—say at B'. Preferably it is in the form of a flat plate, as shown in plan in Figs. 1 and 2, in cross-section in Fig. 3, and in side view in Figs. 4 and 5, but is circular in cross-section 70 where it joins the shuttle, as shown at B². Desirably the free end of the arm has an upward curve.

C is the shuttle-driver; D, the needle; E, the needle-thread; A', the shuttle-thread, and 75 G two thicknesses of fabric.

In Figs. 1 and 4 the shuttle is shown at the extreme end of its forward movement, having passed through the loop E' of the needle-thread, which is engaged by the portion B², 80 the needle D having been drawn up, as in Fig. 4. The shuttle now commences its backward movement, and the loop slips forward along the arm B. In Figs. 2 and 5 the shuttle has completed its backward movement 85 and again begun to advance, the needle has commenced to ascend, and the shuttle-nose has just engaged the thread to form a second loop, while the first loop is free to slip off the arm B and be drawn up tight to the fabric 90 by the action of the shuttle in forming the second loop. The slack is thus taken up without having passed a second time through the eye of the needle.

The shuttle-thread acts in the usual manner, as shown at A', Fig. 4. Its action is not modified in any way, and it is therefore omitted in the other figures for the sake of clearness.

The shape and size of the arm B may vary 100 according to the material to be sewed or the type of machine, &c.

I claim—

1. A vibratory shuttle provided with an

arm to retain the loop of the needle-thread during the reverse movement of the shuttle, the arm being secured near the heel of the shuttle and extending in a plane above the 5 lower edge of the shuttle in the direction of the shuttle-nose, substantially as described.

2. A vibratory shuttle provided with an arm to retain the loop of the needle-thread during the reverse movement of the shuttle, 10 the arm being secured near the heel of the shuttle, and having its free end terminated between the heel and the nose of the shuttle, substantially as described.

3. A vibratory shuttle provided with an 15 arm to retain the loop of the needle-thread during the reverse movement of the shuttle, the arm being secured near the heel of the shuttle, and extending in the direction of the nose of the shuttle, the arm having its outer 20 edge curved, and being of greatest width at its center, substantially as described.

4. A vibratory shuttle provided with a loop-retaining arm secured near the heel thereof,

the arm extending in the direction of the shuttle-nose and thereby adapted upon the 25 reverse movement of the shuttle to release the loop at a point where it will not be engaged by the descending needle, substantially as described.

5. A lock-stitch vibratory shuttle provided 30 with a loop-retaining arm secured near the heel of the shuttle, the arm extending in the direction of the shuttle-nose, but terminating short of the shuttle-nose and thereby adapted upon the reverse movement of the 35 shuttle to release the loop at a point where it will not be engaged by the descending needle, substantially as described.

In witness whereof I have hereto set my hand in the presence of the two subscribing 40 witnesses.

HARRIET RUTH TRACY.
